UNITED STATES PATENT OFFICE.

GILBERT E. DE HAVEN AND OSCAR G. SCHAAF, OF SAN FRANCISCO, CALIFORNIA,
ASSIGNORS TO UNDERWOOD COMPUTING MACHINE COMPANY, OF NEW YORK,
N. Y., A CORPORATION OF NEW YORK.

COMBINED TYPEWRITING AND COMPUTING MACHINE.

Application filed September 4, 1920. Serial No. 408,223.

To all whom it may concern:

Be it known that we, GILBERT E. DE HAVEN, a citizen of the United States of America, residing in San Francisco, in the county of San Francisco and State of California, and OSCAR G. SCHAAF, a citizen of the United States of America, residing in San Francisco, in the county of San Francisco and State of California, have invented certain new and useful Improvements in Combined Typewriting and Computing Machines, of which the following is a specification.

This invention relates to combined typewriting and computing machines, and is illustrated as applied to the Underwood book-keeping machine shown in Patent to F. A. Hart, No. 1,270,411, dated June 25, 1918. Said machine is provided with one or more registers, each provided with a set of computing elements arranged in denominational order, which are operated individually by denomination-selecting mechanism as the typewriter carriage passes through a computing zone, and the digits that are typed by the various numeral-keys are set up by means of indexing devices on the computing elements. Subsequently, the number may be run into the register dial-wheels.

The denomination-selecting mechanism includes a selector which operates successively certain jacks associated with the computing elements to set the latter.

A cam-roller is engageable by a normally ineffective selector on the typewriter carriage to determine the active period of the computing mechanism in the travel of the carriage. When the carriage is returned to begin a new line of writing, the selector snaps past the jacks, causing considerable noise and adding to the wear of the machine, especially when several selectors are used, and when the carriage is returned rapidly, as, for example, by a motor.

A feature of this invention is the rendering of the denomination-selecting mechanism ineffective, or the silencing thereof so that

no parts thereof can be engaged by the carriage, and to afford free movement of the carriage when it is being returned to the beginning of a new writing line. To this end, provision is made to automatically render the computation-controlling cam-roller ineffective, so that the denomination-selectors remain in their ineffective positions relatively to the jacks during the return of the carriage.

The computation-controlling element is held in its ineffective position or the silencing is maintained until the latter part of the return movement of said carriage, when the computation-controlling element resumes its effective position.

The Underwood bookkeeping machine is usually provided with a general-operator key, which starts the motor to drive the general operator to run the set-up number into the register. Said machine is further provided with a carriage-return key, which is effective to start the motor to return the carriage. After a number has been typed in the last column, it is customary to operate the general-operator key to run in the number, and then actuate the carriage-return key to effect the return of the carriage. In practice, it happens that the operative sometimes forgets to actuate the general-operator key, but effects the return of the carriage, and proceeds to set up another number before the previously set-up number is run into the register, consequently causing an erroneous computation when the general operator is actuated to run in the last set-up number.

An object of this invention is to obviate the afore-mentioned difficulty. This may be done by means operable by the carriage-return key to effect the return of the carriage and cause the general operator to function, to run in the number, simultaneously.

A further feature of the invention is the rendering of the numeral-keys ineffective while the carriage is being returned to its initial writing position, so as to prevent the

numeral-types from striking the platen, by a premature operation thereof, or, in other words, while the carriage is returning.

Another feature of the invention relates 5 to restoration of the state of the machine to addition when the carriage is returned from a subtraction zone.

Other features and advantages will hereinafter appear.

10 In the accompanying drawings,

Figure 1 is a sectional side elevation of the machine, showing the invention applied thereto.

15 Figure 2 is a detail view of the carriage escapement mechanism.

Figure 3 is a side view, partly in section, of the lower part of the machine, showing the motor and the connection to the general operator.

20 Figure 4 is a skeleton perspective view of the parts, as seen from the rear and upper left-hand corner of the machine.

Figure 5 is a circuit diagram, showing the motor and two switches connected therein.

25 Figure 6 is a detail top plan view, showing the retaining means to hold the computation-determining element in its ineffective position.

Numeral-keys 9 and alphabet-keys 10, when 30 depressed, swing key-levers 11 and 12, respectively, about a fulcrum rod 13, to actuate bell-cranks 14, to swing type-bars 15 upwardly and rearwardly to cause types 16 thereon to print against the front side of a 35 platen 17, which carries a work-sheet (not shown). The platen is rotatably mounted in a carriage 18, supported to travel on rails 19 and 20 on a main frame 21, and is urged from right to left by a spring-drum 22, connected to the right-hand end of the carriage by a strap 23, so that it may be fed to a new letter-space position at each type stroke.

To effect the letter-spacing movements of the carriage, each type-bar 15 is provided 45 with a heel 24 to engage a universal bar 25 to move the latter rearwardly against the tension of a return spring (not shown). Thus, the universal bar is reciprocated at each type stroke, and consequently a dog 50 rocker 26, engaged by a cross-bar 27 of the universal bar 25, is operated to reciprocate a loose dog 28 and a fixed dog 30, between the teeth 31 of an escapement-wheel 32, to effect a letter-space movement of the escapement-

55 wheel and the carriage; the escapement-wheel 32 having the usual one-way driving pawl connection 33 with a pinion 34, meshing with a feed-rack 35 pivoted at 36 on the carriage 18.

60 While the digits of a number are being typed, they may be set up on computing elements or bars 37 arranged in descending denominational order from left to right of the machine. The computing bars are provided at their forward end with racks 38

geared to dial-wheels 40 of a register 41, so that the set-up number may be transferred to or run into the dial-wheels.

To set up the digits of a number on the computing bars 37, each bar may be provided 70 with a set of nine indexing devices or pins 42, having values from "1" to "9", inclusive. The indexing pins 42 may be depressed by key-actuated linkages including

setting bars 43, to bring the lower ends of 75 the indexing pins into the path of a cross-bar 44 of a general operator 45. Each linkage with its pin-setting bar 43 may be connected to a rock-shaft 46, there being one

rock-shaft associated with each numeral-key, and each rock-shaft being operable by 80 an arm 47, engaged by a plunger 48 on the corresponding numeral-key lever 11 when the latter is operated. The indexing pins

are normally behind and out of range of the 85 pin-setting bars 43, so that ordinarily the pin-setting bars 43 move down between the pins 42 when the numeral-keys 9 are operated.

When the carriage traverses the computing zone, the computing bars 37 are 90 moved forward individually, in denominational order, to locate the various sets of indexing pins 42 under the pin-setting bars 43. The locating of the indexing pins may 95 be done by denomination-selecting mechanism, hereinafter described, which is actuatable by the carriage 18. Each pin-bar 37 is held in its pin-setting position while the carriage occupies the corresponding denominational position in the computing zone until a digit 100 is typed in said position, so that the indexing pin having a value corresponding to the value of the typed digit may be set or depressed upon the computing bar. Upon the return of the type-key, the carriage moves to 105 the next denominational position, thus allowing the computing bar with the depressed indexing pin to return, while the computing bar of next lower denominational order is moved to its pin-setting position when the 110 next digit may be typed. Thus, the various indexing pins are set on the various computing bars as the digits are typed, while the carriage traverses the computing zone.

The denomination-selecting mechanism 115 for moving the computing bars 37 to their pin-setting positions may comprise a dog or selector 50, mounted on a bar 51 supported on the typewriter carriage. The selector is adjustable lengthwise of the carriage to a column of numbers to be computed, and is held in its adjusted position by a rack-bar 52. The selector normally occupies the ineffective position indicated in

120 dotted lines in Figure 1. When the carriage enters the computing zone, the selector is swung to its effective position by a computation-controlling element in the form of a cam-roller 53, which is engaged by a roller 54 on the selector, so that the selector 125

occupies the effective position indicated in dotted lines in Figure 1. When the carriage enters the computing zone, the selector is swung to its effective position by a computation-controlling element in the form of a cam-roller 53, which is engaged by a roller 54 on the selector, so that the selector 130

rides up on the cam-roller to move a tappet 55 of the selector into engaging relation with a set of jacks 56, pivoted on a rod 57 and arranged from right to left in descending 5 denominational order. The jacks 56 are operated individually as the carriage moves through the computing zone. Each jack depresses a thrust rod 58 to operate an intermediate lever 60 associated therewith. Each intermediate lever 60 engages with a transposition device 61, to operate a bell-crank 62 about a fixed pivot 63, and move the associated computing bar 37 forward against a return spring 64 to its pin-setting position. Thus, the computing bars 37, which are arranged in descending denominational order from left to right, are rendered effective through the transposition devices 61 by the jacks 56, which are arranged in descending order from right to left; the jacks being so arranged that the carriage, which moves from right to left, may engage with the jacks in their proper denominational order.

25 It will be understood that a plurality of selectors may be used to effect the transfer of computations in several columns (cross computation) into a single register.

It will further be understood that a plurality of registers may be used, each comprising a set of computing bars 37 underlying the pin-setting bars 43; that each register may have associated therewith a computation-controlling element 53 and one or more selectors 50; and that, by a suitable arrangement of the selectors on the carriage, a number typed in a single column may be set up on the computing bars of several registers.

40 After a number has been set up on the computing bars of one or more registers, the general operator 45 may be caused to cycle by means of a motor 59 (Figure 3) to run the number into the dial-wheels. To start the motor, there may be provided mechanism which may be like that shown in the patent to A. J. Wood, No. 1,299,646, dated April 8, 1919. This mechanism may include a key 65, herein referred to, for clearness, as a general-operator key. Said key may be arranged at the right-hand side of the machine, and may be depressed, against the tension of a return spring 66, to operate a lever 67, engaging with the outer

55 end of a horizontally-disposed lever 68 (Figures 1 and 4), to swing the latter about a fixed pivot 70. The lever 68 extends inwardly to about the middle of the machine, where it engages to raise a trip pin 71 out of the path of an ear 72 on a clutch member or disk 73, carried by studs 74, which extend through slots 75 in the clutch member and are secured to a disk 76. The disk 76 is fixed to a shaft 77, which may be driven by the motor 59 through a worm 78,

on the motor shaft 80, meshing with a worm-wheel 81. The worm-wheel is loosely mounted on the shaft 77, so that the motor may rotate independently of the shaft 77. When the trip pin 71 is raised, the 70 disk 73 is given a preliminary movement by means of a spring (not shown) to effect a connection between the worm-wheel 81 and the shaft 77. For this purpose, the clutch member 73 may be provided with 75 studs 82, which allow pivoted pawls 83 on the disk 76 to engage a ratchet-wheel 84, rigidly secured to the worm-wheel 81, thus coupling the shaft 77, to which the disk 76 is secured, with the motor by the preliminary movement of the clutch member 73. The motor 59, which may be caused to run intermittently, may be started by a switch 85^a, (Figure 5), connected in a motor circuit comprising conductors 85 and 86. The 85 switch may be closed by an extension 87^a on said disk or clutch-rendering member 73, (Figure 3).

After the shaft 77 is connected and the motor switch 85^a is closed, the shaft 77 rotates to drive the general operator 45 to run the set-up number into the dial-wheels. To drive the general operator, the shaft 77 is provided at its left-hand end with a crank-arm 87, having a crank-pin 88 engaging a 90 block 90, the latter sliding up and down in a slot 91 of a cross-head 92, as the arm 87 rotates with the shaft 77, to move the cross-head forwardly and backwardly. The cross-head is guided by a horizontal rod 93 100 moving in bearings 94 at each end thereof, and is provided at its upper end with an arm 95 engaging a fork 96, secured to the left-hand one of two guide-bars 97 of the general operator 45. Thus, as the cross-head 92 is 105 reciprocated, the general operator is moved therewith to run the number into the register on its forward stroke by means of the cross-bar 44, and to restore the computing bars 37 on the rearward stroke when the cross-bar 110 44 engages projections 98 on said computing bars. The indexing pins are restored in the usual way at the return stroke of the general operator. The motor is stopped automatically and the shaft 77 is disconnected from 115 the motor after the general operator is restored, as described in the Wood patent hereinbefore referred to.

The carriage may be speedily returned to the beginning of a new line, there being provided, for this purpose, carriage-returning means which may be similar to that disclosed in the patent to F. A. Hart, No. 1,238,908, dated Sept. 4, 1917. The carriage-returning means may comprise a starting key 100 (Figures 1 and 4), which, when depressed, swings a bell-crank lever 101 about a pivot 102, against the tension of a return spring 103, to release a slide 104 by means of a pivoted cam member 105 on said 130

slide 104. The cam member 105 is engaged by a nose 101^a on the lever 101, to raise the slide 104 to release it from a front plate 106, which engages in a notch 107 in the 5 slide 104. The slide 104, upon its release, is moved rearwardly by a spring 108, to rock a shaft 109 by means of an arm 110, secured to said shaft and connected to said slide. The shaft 109 is rocked by the slide 104 to 10 connect a pinion 111, meshing with a rack 112 on the carriage, with a shaft 113 by sliding the pinion on said shaft into engagement with a clutch member 114 secured to said shaft. Thus, the driving connection 15 is completed between the rack 112 on the carriage and the shaft 113, after which the carriage may be returned by the motor 59, which, when started, drives a counter-shaft 115 by means of a belt 116; the driving connection 20 between the counter-shaft 115 and the shaft 113 comprising a belt 117. The connection from the rock-shaft 109 to the pinion 111 may comprise an upwardly-extending arm 118, connected by a link 120 to 25 a downwardly-extending arm 121 on a shaft 122, to rock the latter; the shaft 122 having an arm 123 projecting into an annular groove 124 of the pinion 111, so that the pinion 111 may be moved into and out of engagement with the clutch member 114. 30

The motor 59 is normally at rest and a second switch 125 (Figures 4, 5 and 6) may be closed to start the motor when the pinion is connected with the clutch member 114. 35 For this purpose, the rock-shaft 109, which is operated by the spring 108 through the intermediary of the slide 104, is provided with a downwardly-extending arm 126, having connected thereto a yieldable thrust-bar 40 127 composed of two members 128 and 129 with an intermediate spring 131 connected between them. The thrust-bar is moved rearwardly, when the slide 104 is released by the carriage-return key, to operate a 45 pivoted member of the switch 125 to close said switch to start the motor 59. Thus, the pinion 111 and the switch 125 are both operated by the carriage-return starting slide 104 and may be operated simultaneously. 50

From the foregoing, it will be understood that the general-operator key 65 and the carriage-return key 100 are each operable to render a clutch effective and close a 55 switch, so that the motor may drive the general operator and the carriage-return mechanism, respectively, and that the general operator may be actuated independently of the carriage-return mechanism, and vice 60 versa.

The carriage-return motor-switch 125 remains closed until the carriage reaches the end of its return movement, when it is automatically opened to stop the motor. To 65 this end, there is provided on the carriage

18 a projection 132, which engages a cam 133 associated and adjustable with the usual right-hand margin-stop 134. The cam 133 is splined to a shaft 135 and, when operated, rocks the latter to pull forwardly a link 136, 70 connected to an arm 137 on said shaft 135. The link 136 is connected to operate a second link 138, guided by a screw 140 on the right-hand end of the main frame 21. The link 138 is connected to an arm 141 to rock the 75 shaft 122 back to normal position; thus moving the pinion 111 out of engagement with the clutch member 114, by means of the arm 123 engaging said pinion. It will be seen that the rock-shaft 109, which is 80 connected to the shaft 122, is also operated, and consequently the thrust-bar or switch-plunger 127 is restored to normal position, thus permitting the switch 125 to be opened, which may be done by means of a spring. 85

When the shaft 109 is rocked back to normal position, the slide 104 moves forwardly against the tension of the spring 108 and catches on the front plate 106 to be retained in normal position. 90

After a number has been typed in a column, the carriage may be returned by means of the carriage-return key 100 to the first position in the same column, or to the first position in another column, according 95 to the setting of the right-hand margin-stop. Before the next number is typed, however, it is necessary to run in the set-up number, which may be effected by means of the general-operator key 65. In practice, 100 the operative sometimes forgets to run in the set-up number and proceeds to type the next number, thus setting up another number on the computing bars, in addition to the one already set thereon. Consequently, 105 when the general-operator key is actuated to run in the last typed number, an erroneous result is obtained.

Provision is herein made to obviate the foregoing. To this end, a connection may 110 extend from the carriage-return key 100 to render effective the clutch comprising the pawls 83 and ratchet wheel 84, to effect the drive of the general operator at each actuation of said key. Said connection may comprise a link 142 suitably connected at 143 to the carriage-return key-lever 101, so that the latter, when depressed, swings an arm 144, by means of the link 142, to rock a shaft 145 to which the arm 144 is secured. The 115 rock-shaft 145 may extend across near the front of the machine and may be supported in brackets 146 on the computer frame 147. The rock-shaft is provided, near the middle, with an arm 148 to engage a lever 150 to 120 swing the latter about its pivot 151 on a bracket 152 secured to a base plate 153. The rear end of the lever 150 engages the inner end of the horizontally-disposed operating lever 68, to lift the trip pin 71 out of en- 125 130

gagement with the disk 73 to render effective said clutch. Thus, the general operator 45 is caused to cycle to run in the number and the carriage is returned by means of 5 the motor 59, which is started by the switch 125. The clutch is automatically rendered ineffective when the number is run in, as previously described.

By inspection of Figure 5, it will be seen 10 that the two motor switches 85^a and 125 are connected in multiple in the motor circuit, comprising the conductors 85 and 86, and each switch is connected in series with the motor 59. It will be understood that 15 the switch 85^a may be closed by the general-operator key 65 and automatically opened to stop the motor when the general operator has completed its cycle. The motor-switch 125, which is under the control of the carriage-return key 101, is provided so that the motor may continue to run if the general operator completes its cycle before the carriage is completely returned to its initial writing position, when the switch is automatically opened by means of the mechanism 20 operated by the projection or lug 132 on the carriage. It will further be understood that both switches are closed when the carriage-return key is operated, and that 25 the closing of the switch 85^a is merely incidental, as it is controlled by the disk or clutch-controlling member 73.

It is desirable to render the computation-controlling elements or cam-rollers 53 ineffective or to silence the denomination-selecting mechanism during the return of the carriage, so as to prevent engagement of the tappets 55 with the jacks 56, which ordinarily causes considerable noise and wear of 30 the machine, and also adds to the resistance offered to the return of the carriage. To this end, the cam-rollers 53 may be rendered ineffective automatically by means controlled by the general operator 45. Said means may 35 comprise a bell-crank member 154, pivoted at 155 on the computer frame 147. The bell-crank has a finger 156, which normally lies in a depression 157 in the left-hand guide-bar 97 of the general operator. As the general operator moves forwardly, the bell-crank member is swung about its pivot in a clockwise direction by a cam 158 on the guide-bar 97. An upwardly-extending arm 160 of said bell-crank engages a projection 40 161 on a link 162, to move the latter rearwardly; said link being guided at its forward end by a pivoted arm 163 and connected at its rear end to swing a bell-crank member 164 about a fixed pivot 165. The bell- 45 crank 164 comprises an arm 166, engaging an arm 167 secured to a shaft 168 to rock the latter in a clockwise direction. On the rock-shaft 168 may be secured several pairs of arms 170, each pair to support a cam- 50 roller 53, so that all of the cam-rollers may

be swung to their ineffective positions, indicated by dot-and-dash lines in Figure 1, and against the tension of a spring 171 when the shaft 168 is rocked. Thus, the selectors remain in their lowermost or ineffective positions, also indicated by dot-and-dash lines in Figure 1, when the carriage is returning. 70

It will be understood that the general operator is effective to render and maintain the cam-rollers ineffective while said general operator is cycling, during which time the carriage may be returned through a plurality of letter-spaces. The general operator may, however, return to its normal position before the carriage is fully restored to its initial writing position, and consequently the cam-rollers 53 would, under ordinary conditions, resume their normal effective positions. Provision is herein made to retain the cam-rollers in their ineffective positions 80 until the end of the return stroke of the carriage. For this purpose, there may be provided a latch 172 to co-operate with the bell-crank 164, which is used to throw out the cam-rollers 53. The latch 172 normally occupies 85 an ineffective position (Figures 4 and 6), so that the bell-crank 164 may be operated to lock the numeral-keys 9, through the intermediary of the cam-roller 53, as hereinafter described, to obviate the possibility 90 of setting the indexing pins 42 while the general operator is in actuation. 95

The latch 172 is rendered effective, when the carriage-return key 100 is actuated, by means of a link 173 (Figures 4 and 6), connected to the arm 110 on the shaft 109, which is operated by the carriage-return starting slide 104 when the latter is released by the carriage-return key 100; the latch being moved to its effective position, indicated in 100 dot and dash lines in Figure 6. As soon as the cam-rollers are moved to their ineffective positions through the medium of the bell-crank 164, a projection 174 on said bell-crank snaps behind the latch 172, and consequently 105 the cam-rollers are retained in their ineffective positions until the latch is rendered ineffective. The latch 172 is pivoted at 175 on a fixed bracket 176 and is moved to its effective position by a spring 177 when the link 110 115 178 is moved rearwardly. The connection 178 of the latch or pawl 172 with the link 173 is such as to permit a slight movement of the pawl independently of the link 173 when the projection 174 snaps behind the 120 pawl. The latch 172 remains in its effective position until the carriage reaches the end of its return stroke, when the projection 132 on the carriage engages the cam 133, to rock the shaft 135 and the shaft 109 connected to 125 the latter, to restore the latch 172 to its normal position by means of the link 173. Thus, the bell-crank 164 is released and the cam-rollers are drawn back to their normal positions by the spring 171. The carriage-re- 130

turn starting slide 104 is restored to catch on the plate 106, as previously described.

From the foregoing, it will be understood that as the carriage 18 passes forwardly 5 through the computing zone, the selector of the denomination-selecting means is held in its effective position by the co-operating member or cam-roller 53, and that when the carriage-returning means, including the 10 motor 59, is started by the carriage-return key 100, the motor becomes effective to actuate the driving means, including the shaft 77 and the cross-head 92, to cycle the general operator, which, by means of the cam 15 158 and the bell-crank 154 operated thereby, renders the cam-roller 53 ineffective so as to be out of the path of the selector when the carriage is returned. It will further be understood that the cam-roller is held in 20 its ineffective position by the latch 172, which is operated at the end of the return movement of the carriage to release the cam-member of the denomination-selecting means, so that the cam-member may resume 25 its effective position.

To lock the numeral-keys 9 so as to obviate the possibility of setting the indexing pins 42 while the general operator is cycling, there may be provided mechanism like 30 that shown in the patent to W. L. Gumprecht, No. 1,237,895, dated August 21, 1917. This mechanism may include a lever 180, which is swung about its pivot 181 by one of the cam-rollers 53 when the cam-rollers 35 are moved to their ineffective positions by the general operator 45. The lever 180 pushes downwardly on a rod 183 to rock a bell-crank 184, to pull rearwardly on a link 185. The link 185 is connected by an arm 40 186 to a shaft 187, to rock the latter to move a dog 188 between locked pawls 190, which prevent the depression of the numeral-keys through the intermediary of stems 191 on the plungers 48, as clearly shown in the 45 above-mentioned Gumprecht patent.

Since the numeral-keys are locked by means including the lever 180 which is engaged by the cam-roller 53, and since the cam-roller is operated to render it ineffective 50 relatively to the selectors 50 when the carriage is returned, it will be understood that the depression-preventing means, including the pawls 190, is operated to prevent the actuation of the numeral-keys while the 55 carriage is returning.

It will be understood that the driving means, including the general operator for the computing bars, has associated therewith the clutch comprising the pawls 83 60 and ratchet 84, which is normally ineffective; that the carriage-returning means, including the shaft 113, has also associated therewith a normally ineffective clutch comprising the pinion 111 and the clutch member 114; and that the carriage-return

key 100 is effective to render both clutches effective and close the motor-switch 125 simultaneously to start the motor, so that the set-up number may be run in and the carriage returned.

70

The computer frame or casing 147 may be connected in any convenient manner with the main frame 21, so that they may be conveniently removed or assembled as a unit on the base plate 153. To assist in 75 assembling, the computer casing may be provided with conical studs 192, received in holes 193 in bosses 194 on said base plate.

It will be seen that the pin-operating lever 68 is pivoted on the base plate 153, 80 while the actuating arm 148 and the rock-shaft 145 are carried by the computer frame 147. This arrangement affords a broken connection between the arm 148 and the lever 150, to permit the computer casing to 85 be readily assembled and removed from the base plate. The connections of the cross-head 92 with the general operator 45, and the general-operator key-lever 67 with the pin-retracting lever 68 also permit of ready 90 attachability or detachability of the computer casing with the parts carried thereby. When removing the computer casing, the belt 117 may be slipped off one of the pulleys 95 in the usual way.

95

The state of the machine is normally that of addition, and the machine may be set to a state of subtraction by mechanism which may be similar to that disclosed in the patent to H. Hanson, No. 1,278,812, dated September 10, 1918, and the patent to O. Minton, No. 1,280,965, dated September 24, 1918; subtraction being performed by the well-known complementary method. The machine may be set to the state of subtraction automatically or manually, as described in the above-mentioned Minton patent. To set it manually, there is provided a key 195 at the forward end of a thrust-rod 196, which may be pushed rearwardly to rock a shaft 197 100

100

105 to a shaft 197, to rock the latter to move a dog 188 between locked pawls 190, which prevent the depression of the numeral-keys through the intermediary of stems 191 on the plungers 48, as clearly shown in the 110 above-mentioned Gumprecht patent.

110

Since the numeral-keys are locked by means including the lever 180 which is engaged by the cam-roller 53, and since the cam-roller is operated to render it ineffective 115 relatively to the selectors 50 when the carriage is returned, it will be understood that the depression-preventing means, including the pawls 190, is operated to prevent the actuation of the numeral-keys while the 120 carriage is returning.

115

It will be understood that the driving means, including the general operator for the computing bars, has associated therewith the clutch comprising the pawls 83 125 and ratchet 84, which is normally ineffective; that the carriage-returning means, including the shaft 113, has also associated therewith a normally ineffective clutch comprising the pinion 111 and the clutch member 114; and that the carriage-return

125

130

the complements of the rock-shafts. Consequently, the numeral keys 9, when operated, while the machine is in a state of subtraction, are effective to set the pins having values corresponding to the complements of the numeral keys, and, as a result, the complement of a number being typed is set up on the pin-bars, which may then be run into the register by means of the general operator.

The subtraction-setting slide 202 may be restored to its normal position by means of the cross-bar 44 of the general operator, which engages during its forward stroke 15 with a projection 209 on the subtraction-setting slide to push the latter forwardly. After the subtraction slide has been restored, the pawl 200 again snaps into the notch 201 by a spring 210 connected to the subtraction-setting thrust-bar 196.

From the foregoing, it will be understood that when the return of the carriage 18 is effected from the subtraction zone, the general operator is caused to functionate, thus 25 causing the subtraction-setting slide 202 and connecting mechanism to be restored by the general operator, and consequently restoring the state of the machine to that of addition. With this arrangement, instead of requiring two operations, as heretofore, to return the carriage and restore the machine to addition, only one operation is necessary, that of returning the carriage; the machine being restored to the state of addition automatically 35 during the return of the carriage, the latter being effected by means of the key 100.

Variations may be resorted to within the scope of the invention, and portions of the 40 improvements may be used without others.

Having thus described our invention, we claim:

1. In a combined typewriting and computing machine, the combination of a carriage, 45 computing mechanism, controlling means co-operating with said carriage to govern the active period of the computing mechanism during the travel of said carriage, a finger-piece, finger-piece-controlled means 50 to return said carriage, and means actuatable by said finger-piece to silence and maintain said controlling means silenced during the return of said carriage through a plurality of letter-spaces.

2. In a combined typewriting and computing machine, the combination of a carriage, computing mechanism, controlling means co-operating with said carriage to govern the active period of said computing 55 mechanism in the travel of said carriage, carriage-returning means, operating means for said computing mechanism, controllable by said carriage-returning means and means controllable by the operating means and by 60 said carriage-returning means to silence

and maintain the controlling means silenced during the return of said carriage through a plurality of letter-spaces.

3. In a combined typewriting and computing machine, the combination of a carriage, 70 computing mechanism, controlling means co-operating with said carriage to govern the active period of said computing mechanism in the travel of said carriage, carriage-returning means, driving means for said computing mechanism, means actuatable by the driving means to silence the controlling means, and means controllable by said carriage-returning means to throw said driving means into operation and to maintain the controlling means silenced after it has been silenced by the driving means.

4. In a combined typewriting and computing machine, the combination of a carriage, computing mechanism, a denomination-selector on said carriage, means co-operating with said selector during the travel of the carriage to determine the active period of the computing mechanism, carriage-returning means, and means, thrown 85 into action by actuation of said carriage-returning means, to automatically silence and maintain the co-operating means silenced to render the denomination-selector ineffective during the return of the carriage 90 through a plurality of letter-spaces.

5. In a combined typewriting and computing machine, the combination of a carriage, computing mechanism, a denomination-selector on said carriage, means co-operating with said selector during the 100 travel of the carriage to determine the active period of the computing mechanism, carriage-returning means, means, thrown into action by actuation of said carriage-returning means, to automatically silence and maintain the co-operating means silenced to render the denomination-selector 105 ineffective during the return of the carriage through a plurality of letter-spaces, and means to render the co-operating means effective at the end of the return movement of said carriage.

6. In a combined typewriting and computing machine, the combination of a carriage, computing mechanism, denomination-selecting mechanism for said computing mechanism, said denomination-selecting mechanism comprising a selector on said carriage and a set of jacks to be engaged by 115 said selector, means co-operating with said selector to render the selector effective when the carriage passes forwardly through a computing zone, carriage-returning means and means thrown into action by actuation 120 of said carriage-returning means, to automatically render the co-operating means ineffective and retain it ineffective when the carriage is returned through a plurality of letter-spaces.

7. In a combined typewriting and computing machine, the combination of a carriage, computing mechanism comprising denomination-selecting mechanism effective as the carriage passes forwardly through a computing zone, the denomination-selecting mechanism comprising a selector, means to hold said selector in effective position while the carriage traverses the computing zone, carriage-returning means and means thrown into action by actuation of said carriage-returning means to render and maintain the holding means ineffective when the carriage is returned through a plurality of letter-spaces.
8. In a combined typewriting and computing machine, the combination of a carriage, computing mechanism comprising a denomination-selecting mechanism, the denomination-selecting mechanism comprising a selector, means to hold said selector in effective position while the carriage traverses a computing zone, carriage-returning means, means, thrown into action by actuation of said carriage-returning means, to render the holding means ineffective while the carriage is returning, and means to render the holding means effective at the end of the return stroke of said carriage.
9. In a combined typewriting and computing machine, the combination of a carriage, computing mechanism comprising a denomination-selecting mechanism effective as the carriage passes forwardly through a computing zone, the denomination-selecting mechanism comprising a selector, means to hold said selector in effective position while the carriage traverses the computing zone, carriage-returning means, means, thrown into action by actuation of said carriage returning means, to render the holding means ineffective when the carriage is returned, and means to lock the holding means in ineffective condition while the carriage is returning.
10. In a combined typewriting and computing machine, the combination of a carriage, computing mechanism comprising a denomination-selecting mechanism effective as the carriage passes forwardly through a computing zone, the denomination-selecting mechanism comprising a normally ineffective selector, means to hold said selector in effective position while the carriage traverses the computing zone, carriage-returning means, and means, thrown into action by said carriage-returning means, to automatically render and maintain the holding means ineffective when the carriage is returned through a plurality of letter-spaces.
11. In a combined typewriting and computing machine, the combination of a carriage, computing mechanism comprising a denomination-selecting mechanism, the denomination-selecting mechanism comprising a selector, a cam member to hold said selector in effective position while the carriage traverses a computing zone, carriage-returning means operable by said carriage-returning means to render said cam member ineffective while the carriage is returning, and means operable by the carriage to render the cam member effective at the end of the return stroke of said carriage.
12. In a combined typewriting and computing machine, the combination of a carriage, computing mechanism comprising a denomination-selecting mechanism effective as the carriage passes forwardly through a computing zone, the denomination-selecting mechanism comprising a selector, a cam member to hold said selector in effective position while the carriage traverses the computing zone, carriage-returning means, means operable by said carriage-returning means to render said cam member ineffective when the carriage is returned, a latch to hold said cam member ineffective while the carriage is returning, and means to release said latch at the end of the return movement of said carriage.
13. In a combined typewriting and computing machine, the combination of a carriage, computing mechanism comprising denomination-selecting mechanism, the denomination-selecting mechanism comprising a normally ineffective selector, means to hold said selector in an effective position while the carriage travels forwardly through a computing zone, carriage-returning means including a motor, and means actuatable by said motor to render the first-mentioned means ineffective when the carriage is returned by said motor.
14. In a combined typewriting and computing machine, the combination of a carriage, computing mechanism comprising denomination-selecting mechanism, the denomination-selecting mechanism comprising a selector, a cam member to hold said selector in its effective position while the carriage traverses a computing zone, carriage-returning means including a motor, and means actuatable by said motor to render the cam member ineffective when the carriage is returned by said motor.
15. In a combined typewriting and computing machine, the combination of a carriage, computing mechanism comprising denomination-selecting means, effective as the carriage passes forwardly through a computing zone, the denomination-selecting means comprising a selector, a cam member to hold said selector in its effective position while the carriage travels forwardly through the computing zone, carriage-returning means including a motor, motor-controlling means, means to actuate the motor-controlling means to start said motor, means actuatable by the motor to render the cam member ineffective.

tive when the carriage is returning, means to automatically actuate the motor-controlling means to stop the motor, and means actuatable by the motor-controlling means to render the 5 cam member effective.

16. In a combined typewriting and computing machine, the combination of a carriage, computing mechanism comprising a general operator, driving means for the general operator, a motor to actuate said driving means, carriage-returning mechanism operable by said motor, means to start said motor to return said carriage, said means being also effective to render the driving 10 means effective, denomination-selecting means, and means operable by the general operator to render said denomination-selecting means ineffective while the carriage is being returned.

20 17. In a combined typewriting and computing machine, the combination of a carriage, computing mechanism comprising a general operator, driving means for the general operator, a motor to actuate said driving 25 means, carriage-returning mechanism operable by said motor, a key to start said motor to return said carriage, means operable by said key to render the driving means effective, denomination-selecting means, means 30 actuatable by the general operator to render said denomination-selecting means ineffective while the carriage is being returned, normally ineffective retaining means, and means operable by said key to render said retaining 35 means effective, said retaining means being effective to hold the denomination-selecting means ineffective until the carriage is returned.

18. In a combined typewriting and computing machine, the combination of a carriage, computing mechanism comprising a general operator, driving means for the general operator, a motor to actuate said driving 40 means, carriage-returning mechanism operable by said motor, a key to start said motor to return said carriage, said key being also effective to render the driving means effective, denomination-selecting means comprising a selector, a cam member to be engaged by the selector as the carriage 45 traverses a computing zone, means actuatable by the general operator to render said cam member ineffective while the carriage is being returned, a normally ineffective latch, 50 means operable by said key to render said latch effective, said latch being effective to retain the denomination-selecting means ineffective until the carriage is returned, and means to actuate said latch to release said 55 cam member at the end of the return stroke of said carriage.

19. In a combined typewriting and computing machine, the combination of a carriage, computing mechanism comprising a 60 general operator, driving means for the gen-

eral operator, a motor to actuate said driving means, carriage-returning mechanism operable by said motor, a key to start said motor to return said carriage, means actuatable by said key to render the driving means effective, denomination-selecting means, means actuatable by the general operator to render said denomination-selecting means ineffective while the carriage is being returned, a normally ineffective latch, means 70 operable by said key to render said latch effective, said latch being effective to retain the denomination-selecting means ineffective until the carriage is returned, and means operable at the end of the return stroke of the 75 carriage to actuate said latch to release the denomination-selecting means.

20. In a combined typewriting and computing machine, the combination of a carriage, computing mechanism comprising 80 computing elements, denomination-selecting means, and a general operator for the computing elements, carriage-returning mechanism, means to actuate the general operator and the carriage-returning mechanism, and 85 means actuatable by the general operator to render the denomination-selecting means ineffective while the carriage is returning.

21. In a combined typewriting and computing machine, the combination of a carriage, computing mechanism comprising 90 computing elements, denomination-selecting means, and a general operator, carriage-returning mechanism, means to actuate the general operator and the carriage-returning 95 mechanism, means actuatable by the general operator to render the denomination-selecting means ineffective while the carriage is returning, the general operator being returned to normal position before the return 100 movement of the carriage is completed, and means to retain said denomination-selecting means ineffective until the carriage is returned.

22. In a combined typewriting and computing machine, the combination of a carriage, computing elements, denomination-selecting means for said computing elements, said denomination-selecting means comprising a selector and a co-operating member, 110 a general operator, carriage-returning mechanism, means to actuate the general operator and the carriage-returning mechanism, means actuatable by the general operator to render said co-operating member ineffective 115 while the carriage is returning, the general operator being returned to normal position before the return movement of the carriage is completed, means to retain said co-operating member ineffective until the carriage is 120 returned, and means to actuate the retaining means to release the co-operating member at the end of the return stroke of the carriage.

23. In a combined typewriting and com- 130

puting machine, the combination of a carriage, computing mechanism comprising denomination-selecting means and a general operator, carriage-returning mechanism, 5 means to actuate the general operator and the carriage-returning mechanism, means actuatable by the general operator to render the denomination-selecting means ineffective while the carriage is returning, the general 10 operator being returned to normal position before the return movement of the carriage is completed, means to retain said denomination-selecting means ineffective until the carriage is returned, and means operable by 15 said carriage at the end of its return movement to operate said retaining means to release the denomination-selecting means.

24. In a combined typewriting and computing machine, the combination of a carriage, computing elements, denomination-selecting means for said computing elements, said denomination-selecting means being operable while the carriage passes through a computing zone, a general operator for said 25 computing elements, normally ineffective driving means for the general operator, a motor to actuate said driving means, carriage-returning means, a key to start said motor, means operable by said key to render 30 said driving means effective to return said carriage, means actuatable by the general operator to render the denomination-selecting means ineffective, normally ineffective retaining means to hold the denomination-selecting means ineffective while the carriage 35 is returning, said retaining means being rendered effective by said key, means to stop the motor at the end of the return of said carriage, and means operable by said 40 stopping means to render said retaining means ineffective.

25. In a combined typewriting and computing machine, the combination of a carriage, computing mechanism comprising a general operator, driving means for the general operator, starting means for said driving means, carriage-returning means, starting means for said carriage-returning means, and means operable by the carriage-return 50 starting means to actuate the starting means for the driving means.

26. In a combined typewriting and computing machine, the combination of a carriage, computing mechanism comprising a general operator, driving means for the general operator, carriage-returning means, starting means for said carriage-returning means, and means operable by the carriage-return starting means to start said driving 60 means.

27. In a combined typewriting and computing machine, the combination of a carriage, computing mechanism comprising a general operator, driving means for the general operator, connecting means for said

driving means, carriage-returning means, connecting means for said carriage-returning means, a motor to actuate the driving means and the carriage-returning means, and a key to actuate the carriage-return connecting 70 means and the connecting means for the driving means.

28. In a combined typewriting and computing machine, the combination of a carriage, computing mechanism comprising a general operator, driving means for the general operator, carriage-returning means, a motor to actuate the driving means and the carriage-returning means, connecting means for said driving means, a key to actuate said 80 connecting means, connecting means for said carriage-returning means, a key to actuate the carriage-return connecting means, and means operable by the carriage-return connecting key to actuate the connecting means 85 for the driving means.

29. In a combined typewriting and computing machine, the combination of a carriage, computing elements, denomination-selecting means for said computing elements, said denomination-selecting means being operable by said carriage, a general operator for said computing elements, a motor to actuate the general operator, a switch to start said motor, a key to close said switch, carriage-returning 90 means actuatable by said motor, a second switch to start said motor, a key to close both of said switches to start said motor, means operable to render the denomination-selecting means ineffective when the second-mentioned key is 100 operated, means to open the first-mentioned switch when the general operator has completed a cycle, means to retain said denomination-selecting means ineffective after the general operator has completed its cycle, and means to automatically open the second-mentioned switch, and to operate the retaining means 105 to release the denomination-selecting means when the carriage reaches the end of its return movement.

30. In a combined typewriting and computing machine, the combination of a carriage, computing mechanism comprising denominational selecting mechanism including a selector, a cam member to hold said selector in effective position while the carriage traverses a computing zone, a motor, a motor-circuit including a switch, carriage-returning mechanism by which the motor may return the carriage, said carriage-returning mechanism including a clutch to connect the motor with the carriage or to disconnect it therefrom, a controlling member for said clutch and said switch, spring means urging said controlling member to close the switch 110 and render said clutch effective, latching means to hold said controlling member against the action of said spring means, a carriage-return key to release said controlling member, cam-controlling means, where- 115

by the motor may render said cam member ineffective, including a normally ineffective clutch, and means whereby operation of the carriage-return key will render the cam-controlling clutch effective so that the motor will render the cam member ineffective.

31. In a combined typewriting and computing machine, the combination of a carriage, computing mechanism comprising denominational selecting mechanism including a selector, a cam member to hold said selector in effective position while the carriage traverses a computing zone, a motor, a motor-circuit including a switch, carriage-returning mechanism by which the motor may return the carriage, said carriage-returning mechanism including a clutch to connect the motor with the carriage or to disconnect it therefrom, a controlling member for said clutch and a switch, spring means urging said controlling member to close the switch and render said clutch effective, latching means to hold said controlling member against the action of said spring means, a carriage-return key to release said controlling member, cam-controlling means, whereby the motor may render said cam member ineffective, including a normally ineffective clutch, means whereby operation of the carriage-return key will render the cam-controlling clutch effective so that the motor will render the cam member ineffective, and carriage-controlled means for restoring said controlling member to the position at which said latching means becomes effective.
32. In a combined typewriting and computing machine, the combination of a carriage, computing mechanism comprising denominational selecting mechanism including a selector, a cam member to hold said selector in effective position while the carriage traverses a computing zone, a motor, a motor-circuit including a switch, carriage-returning mechanism by which the motor may return the carriage, said carriage-returning mechanism including a clutch to connect the motor with the carriage or to disconnect it therefrom, a controlling member for said clutch and said switch, spring means urging said controlling member to close the switch and render said clutch effective, latching means to hold said controlling member against the action of said spring means, a carriage-return key to release said controlling member, cam-controlling means, whereby the motor may render said cam member ineffective, including a normally ineffective clutch, means whereby operation of the carriage-return key will render the cam-controlling clutch effective so that the motor will render the cam member ineffective, latching means to hold said cam member in ineffective position, and carriage-controlled means for restoring said controlling member to the control of its latching means and

for releasing the cam member from its latching means.

33. In a combined typewriting and computing machine, the combination of a carriage, computing mechanism comprising a register, computing elements upon which a number may be set up, operating means to actuate the computing elements to run the set-up number into the register, carriage-returning means, a motor to actuate the operating means and the carriage-returning means, a clutch to connect the motor with the operating means, a switch for said motor, means comprising a key to render said clutch effective and close the switch simultaneously, means to automatically render the clutch ineffective, when the operating means has completed a cycle, and means to automatically stop the motor when the carriage reaches the end of its return movement.

34. In a combined typewriting and computing machine, the combination of a carriage, computing mechanism comprising denominational selecting mechanism including a selector, a cam member to hold said selector in effective position while the carriage traverses a computing zone, a motor, a motor-circuit including two switches in parallel, carriage-returning mechanism by which the motor may return the carriage, said carriage-returning mechanism including a clutch to connect the motor with the carriage or to disconnect it therefrom, a controlling member for said clutch and one of said switches, spring means urging said controlling member to close the switch associated therewith and render said clutch effective, latching means to hold said controlling member against the action of said spring means, a carriage return key to release said controlling member, cam-controlling means whereby the motor may render said cam member ineffective, including a normally ineffective clutch, and means whereby operation of the carriage-return key will close the other switch and render the cam-controlling clutch effective to permit the motor to render the cam member ineffective.

35. In a combined typewriting and computing machine, the combination of a carriage, computing mechanism comprising a register, computing elements upon which a number may be set up, operating means to actuate the computing elements to run the set-up number into the register, carriage-returning means, a motor to actuate the operating means and the carriage-returning means, a clutch to connect the motor with the operating means, a switch for said motor, means comprising a key-operated lever to close said switch, a rock-shaft operable by the key-lever, a lever operated by said rock-shaft, and means operable by said last-mentioned lever to render said clutch effective.

36. In a combined typewriting and computing machine, the combination of a carriage, computing mechanism comprising a register, computing devices upon which a number may be set up, operating means to actuate the computing devices to run the set-up number into the register, a motor to actuate the operating means, a normally ineffective clutch, an element to render said clutch effective, a key to actuate said element, carriage-returning means comprising a normally ineffective clutch, a carriage-return key to render the last-named clutch effective, and means actuatable by the carriage-return key to actuate said element to render the first-named clutch effective. 70
37. In a combined typewriting and computing machine, the combination of a carriage, computing mechanism comprising a register, computing devices upon which a number may be set up, operating means to actuate the computing devices to run the set-up number into the register, a motor to actuate the operating means, normally ineffective connecting means, an element to render said connecting means effective, a key to actuate said element, carriage-returning means, normally ineffective connecting means for the carriage-returning means, a carriage-return key to render the last-named connecting means effective, and means actuatable by the carriage-return key to actuate said element to render the first-named connecting means effective. 75
38. In a combined typewriting and computing machine, the combination of a carriage, computing mechanism comprising a general operator, numeral keys, carriage-returning means, means to actuate the carriage-returning means and the general operator simultaneously, means actuatable by the general operator to lock the numeral keys while the carriage is returning, and means to maintain the numeral-key-locking means in effective condition. 80
39. In a combined typewriting and computing machine, the combination of a carriage, computing mechanism comprising denominational selecting mechanism including a selector, a cam member to hold said selector in effective position while the carriage traverses a computing zone, a motor, a motor-circuit including two switches in parallel, carriage-returning mechanism by which the motor may return the carriage, said carriage-returning mechanism including a clutch to connect the motor with the carriage or to disconnect it therefrom, a controlling member for said clutch and one of said switches, spring means urging said controlling member to close the switch associated therewith and render said clutch effective, latching means to hold said controlling member against the action of said spring means, a carriage-return key to release said controlling member, cam-controlling means, whereby the motor may render said cam member ineffective, including a normally ineffective clutch, means whereby operation of the carriage-return key will close the other switch and render the cam-controlling clutch effective to permit the motor to render the cam member ineffective, and a separate key for closing the last-mentioned switch and rendering the cam-controlling clutch effective. 85
40. In a combined typewriting and computing machine, the combination of a carriage, computing mechanism comprising denomination-selecting means, the denomination-selecting means being operable by the carriage as it traverses a computing zone, carriage-returning means, means controlled by said carriage-returning means to render the denomination-selecting means ineffective on the return of said carriage, numeral keys, and means operable by the denomination-selecting means when it is rendered ineffective to render the numeral keys ineffective while the carriage is returning. 90
41. In a combined typewriting and computing machine, the combination of a carriage, computing mechanism comprising a computation-determining element, carriage-returning means, means operable by said carriage-returning means to render said element ineffective on the return of said carriage, numeral keys, and means operable by said element to render the numeral keys ineffective while the carriage is returning. 95
42. In a combined typewriting and computing machine, the combination of a carriage, computing mechanism comprising denomination-selecting means, the denomination-selecting means being operable by the carriage as it traverses a computing zone, carriage-returning means; means controlled by said carriage-returning means to render said denomination-selecting means ineffective on the return of said carriage, numeral keys, means to prevent the simultaneous depression of two numeral keys, and means to render the depression-preventing means effective to lock all the numeral keys when the carriage is returning. 100
43. In a combined typewriting and computing machine, the combination of a carriage, computing mechanism, driving means for said computing mechanism, a normally ineffective clutch associated with the computing mechanism, carriage-returning means, a normally ineffective clutch associated with the carriage-returning means, a motor, a motor switch, and a key to render the two clutches effective and to close the switch simultaneously. 105
44. In a combined typewriting and computing machine, the combination with a carriage, computing mechanism comprising a register, numeral keys to set up a number, 110

- a general operator by which the set-up number may be run into the register, and carriage-returning means, of means to start the carriage-returning means and cycle the general operator, mechanism operable by the general operator to render the numeral keys ineffective when the general operator is cycling, and means to retain said mechanism effective until the carriage is returned.
45. In a combined typewriting and computing machine, the combination of a carriage, numeral keys, computing mechanism comprising denominational selecting mechanism including a selector, denomination devices in which digits may be indexed by said keys, a general operator for computing numbers so indexed, a cam member to hold said selector in effective position while the carriage traverses a computing zone, a motor, a motor-circuit including two switches in parallel, carriage-returning mechanism by which the motor may return the carriage, said carriage-returning mechanism including a clutch to connect the motor with the carriage or to disconnect it therefrom, a controlling member for said clutch and one of said switches, spring means urging said controlling member to close the switch associated therewith and render said clutch effective, latching means to hold said controlling member in effective position against the action of said spring means, a carriage-return key to release said controlling member, driving means for the general operator including a normally ineffective clutch, a separate key, means whereby operation of the separate key will render the general operator clutch effective and close the second switch so that the motor will render the cam member ineffective, means whereby actuation of the general operator will shift said cam member to ineffective position, and latching means to hold said cam member in ineffective position.
46. In a combined typewriting and computing machine, the combination of a carriage, computing mechanism which may be set to the state of addition and to the state of subtraction, and means to restore the computing mechanism to the state of addition when the carriage is backed out of a computing zone.
47. In a combined typewriting and computing machine, the combination of a carriage, numeral keys, computing mechanism comprising denominational selecting mechanism including a selector, denomination devices in which digits may be indexed by said keys, a general operator for computing numbers so indexed, a cam member to hold said selector in effective position while the carriage traverses a computing zone, a motor, a motor-circuit including two switches in parallel, carriage-returning mechanism by which the motor may return the carriage, said carriage-returning mechanism including a clutch to connect the motor with the carriage or to disconnect it therefrom, a controlling member for said clutch and one of said switches, spring means urging said controlling member to close the switch associated therewith and render said clutch effective, latching means to hold said controlling member in effective position against the action of said spring means, a carriage-return key to release said controlling member, driving means for the general operator including a normally ineffective clutch, a separate key, means whereby operation of the separate key will render the general operator clutch effective and close the second switch so that the motor will render the cam member ineffective, means whereby actuation of the general operator will shift said cam member to ineffective position, and carriage-controlled means for restoring said controlling member to the control of its latching means and for releasing said cam member.
